Frank J. Kent

UNITED STATES PATENT OFFICE.

GUSTAV R. KELM, OF NEW YORK, N. Y., ASSIGNOR TO WALKER M. LEVETT COMPANY,
OF NEW YORK, N. Y.

MOLD LOCK.

Application filed June 22, 1920. Serial No. 390,862.

To all whom it may concern:

Be it known that I, GUSTAV R. KELM, a citizen of the Republic of Poland, residing at New York, in the county of New York 5 and State of New York, have invented certain new and useful Improvements in Mold Locks, of which the following is a specification.

The present invention relates to locks for 10 securing the parts of a separable or divisible mold together during the casting operation.

The objects of the invention are to provide a simple, practical, efficient and relatively inexpensive lock for this purpose and 15 one which can be readily adjusted to compensate for variations in the mold and to permit of the use of the locking device interchangeably with different molds.

The invention involves a number of novel 20 features of construction, combinations and relations of parts, all of which will be set forth in the following specification.

In the drawing accompanying and forming 25 a part of the specification, I have disclosed the invention embodied in one of its simple practical forms, but wish it understood that modifications may be made without departure from the true spirit and scope 30 of the invention, as will be apparent from the breadth of the appended claims.

Figure 1 in the drawing referred to is a 35 front view of the locking device as applied to an ordinary two-part mold, the release position of the hook being indicated in dotted lines.

Figure 2 is a perspective separated view 40 of the extensible hook structure, showing a portion of the mold element on which it is mounted.

In Figure 1 I have indicated at 5 and 6 the complementary parts of a two-part mold. At opposite sides of the line of separation of these mold parts are mounted the studs 7 and 8 which ordinarily may simply be in 45 the form of pins driven or otherwise engaged in seats provided in the mold parts.

The extensible hook element comprises in 50 the present disclosure an upstanding supporting member 9 having a hub portion pivotally engaged on the stud 8 and provided with a laterally projecting extension or arm 10 on which the adjustable jaw member 11 is slidably supported. This jaw

member for such purpose is shown as provided with a sleeve portion 12 receiving the 55 lateral supporting arm 10 and as also provided with an upwardly projecting lug 13 formed with a screw seat receiving the adjusting screw 14 which has a bearing in the upwardly projecting lug 15 on the pivoted 60 supporting member. This screw is shown as held against longitudinal movement in the bearing lug 15 by means of a set screw 65 16 engaging in the annular groove 17 formed in the shank of the screw. This set screw may be of such a length that it can be turned in far enough to engage and hold the screw 14 in the position to which it is adjusted.

From the foregoing it will be apparent that by means of the adjusting screw the 70 movable jaw may be shifted to increase or decrease the span or working length of the hook and this either before or after the hook is in actual use. In the latter event the hook will operate as a vise to bring the mold 75 parts forcibly into proper engagement. When once the hook is adjusted to the desired length it is preferably locked in this position by means of the set screw described.

This construction, it will be obvious, enables the setting of the hook to correct more or less slight inaccuracies in the mold which may arise from repeated heating and cooling or the wearing of the meeting faces of the 85 mold parts and a further advantage of this construction is that the hooks may be made up in a standard size or sizes and then be applied to and used with molds of different sizes or molds in which the space 90 between the centers of the pins 7 and 8 is variable.

Another important feature of the invention is the provision of the hook with a shoulder to form a bearing for a pinch bar or other device which may be used as an 95 operating lever. In the drawing I have shown such shoulder in the form of a lug 18 projecting angularly from the lower end of the movable jaw member and arranged as the hook is swung over the locking pin 100 to pass beyond the pin so as to constitute a bearing for the pinch bar, indicated at 19, as inserted between the locking pin 7 and the bearing lug 18. When in this relation, standing at the lower side of the locking 105 pin and substantially parallel thereto, it

will be seen, that a powerful closing force may be brought to bear upon the securing hook.

What I claim is:

- 5 1. The combination with a divisible mold, of means for securing the parts of said mold together comprising a shoulder on one of the mold parts, a pivoted hook on the other mold part provided with an extensible jaw 10 for engagement with said shoulder and an actuating lug on the hook and arranged to stand to one side of the locking shoulder when the hook is engaged therewith to provide a hold for a hook operating lever inserted between the locking shoulder and said lug.
- 15 2. The combination with a divisible mold, of means for securing the parts of said mold together comprising a stud on one of said parts and a hook for engagement with said stud pivotally connected with the other mold part, said hook having a jaw engaging over the stud and provided with a projecting lug standing substantially parallel to 20 and at one side of the stud to enable the engagement of a hook operating lever between said lug and the stud.
- 25 3. The combination with a divisible mold, of means for securing the parts of said mold together comprising a stud on one of said parts and a hook for engagement with said stud pivotally connected with the other mold part, said hook having a jaw engaging over the stud and provided with a projecting lug standing substantially parallel to 30 and at one side of the stud to enable the engagement of a hook operating lever between said lug and the stud, said lug being disposed toward the free end of the hook 35 and traveling to the far side of the stud in the engagement of the hook over the stud to thereby enable the use of the lever described for the purpose of more firmly closing the hook over the stud.
- 40 4. The combination with separable mold parts, of a locking shoulder on one of said mold parts, a pivoted support on the other mold part, a holding jaw slidably mounted on said support and arranged to engage the locking shoulder and a screw for adjusting 45 said holding jaw on its support and relative to the locking shoulder.
- 50 5. The combination with separable mold parts, of a locking shoulder on one of said mold parts, a pivoted support on the other mold part provided with a lateral extension, 55 a holding jaw slidably mounted on said ex-

60 tension and projecting therefrom to engage the locking shoulder and a screw connected between the support and sliding jaw for adjusting the jaw on the extension and toward and away from the locking shoulder.

65 6. The combination with separable mold parts, of a locking shoulder on one of said mold parts, a pivoted support on the other mold part provided with a lateral extension, a holding jaw slidably mounted on said extension and projecting therefrom to engage the locking shoulder and a screw connected between the support and sliding jaw for 70 adjusting the jaw on the extension and toward and away from the locking shoulder, said support and the sliding jaw having lugs 75 projecting angularly to one side of the extension and forming bearings for the adjusting screw.

80 7. The combination with separable mold parts, of a locking shoulder on one of said parts, a supporting member pivoted on the other mold part, a jaw member associated with said supporting member and arranged to engage the locking shoulder, one of the members described having a lateral projection and the other of said members having a passage receiving said projection and a screw connecting the two members and adjustable for the purpose of increasing or decreasing the distance between the movable jaw member and the pivot of the supporting member.

85 8. The combination with a divisible mold, of means for securing the parts of said mold together comprising a shoulder on one of the mold parts, a pivoted hook on the other mold part provided with a jaw for engagement with said shoulder and an actuating lug on the hook and arranged to stand to one side of the locking shoulder when the hook is engaged therewith to provide a hold for a hook operating lever inserted between the locking shoulder and said lug.

90 9. The combination with separate mold parts, of a locking shoulder on one of said parts, a pivoted support on the other of said parts, a member engaging said shoulder, said support having a guiding extension on which said engaging member is mounted, and an adjusting member mounted on the support and having a bearing on the engaging member, whereby the engaging member may be moved along the guiding member to compensate for variations in the mold parts.

105 In testimony whereof I affix my signature.
GUSTAV R. KELM.
